Atty's

UNITED STATES PATENT OFFICE.

CHARLES H. TILTON, OF CHICAGO, ILLINOIS.

SHADE MOUNTING.

Application filed November 20, 1922. Serial No. 601,982.

My invention relates to interior decorating, and more specifically to an improved mounting for shades in which the shade roller itself can be adjusted as to height.

5 One object of the invention is to eliminate the possibility of accidentally dislodging the roller from its supporting means, when it is raised or lowered.

10 Another object is to eliminate chattering between the support and the parts slidable thereon.

Another object is to construct a much simpler and cheaper supporting structure for slidably mounted shade rollers.

15 Another object is to provide supporting slides equally suitable for use inside a window casing, or projecting from the face thereof.

Another object is to contribute to cleanliness and sanitation, by providing a mounting permitting removal and replacement of the shade with such ease that it will become common and usual for the housewife or maid, or the janitor of a school or office 25 building, to take down the shade and dust it when cleaning the room.

Further objects and advantages of the invention will become apparent as the description proceeds.

30 In the accompanying drawing:

Fig. 1 is an elevation of a window and window casing equipped with one embodiment of apparatus according to the present invention;

35 Fig. 2 is an enlarged detail front elevation of the fittings at one side of the window;

Fig. 3 is a side elevation of the same fittings;

40 Fig. 4 is a side, and Fig. 5 a front elevation of a modified bracket.

Fig. 6 is a perspective view of a different fitting.

In the embodiment of my invention selected for illustration in Figs. 1, 2 and 3, the window 10 is provided with a shade 12 of any desired type, mounted on a roller 14 of the usual construction. Fittings 16 and 18 support the projecting pins 20 and 22 at the end of the roller, and are themselves slidably guided in vertical movement on wires 24, two for each fitting.

Wires 24 on each side, are tensioned between a lower bracket 26 and an upper bracket 28, each bracket comprising a base portion suitably fastened to the supporting

structure as by screws 30, and a lower shelf 32 and an upper shelf 34, substantially identical, except that the upper shelf carries an eye 36, for a purpose to be explained hereinafter.

60 Wires 24 are formed of a single length of material extending down through shelf 32, across the bottom of the shelf at 38 and up again. The free ends at the top pass through a tensioning block 40, and may be suitably made fast to each other or to the block, as by twisting their ends together, or riveting the end of the wire to form an enlarged head on top of block 40. An adjusting screw 42 is threaded through block 40 and abuts the upper surface of shelf 34, to 65 adjustably tension wires 24.

70 Fittings 16 and 18 are duplicates, except that the aperture in fitting 18 receiving the flat end 22 of the roller structure, has a correspondingly elongated hole, but does not have the usual slot to permit removal of the roller. Each fitting comprises a plate 44 having diverging ears 46 at its upper 75 and lower ear corners, suitably apertured to slide on wires 24.

To slide the shade up and down, a cord 48 rises from fitting 18, passing through the left eye 36 and the right eye also. A similar 80 cord 50 rises from the right hand fitting 16 to pass through the right eye only. Both cords then extend downwardly and are suitably united in a single cord 52, by means of which the height of the shade may be 85 readily adjusted.

I have provided a simple wire clip comprising an eye 54 encircling one of the screws 30 and held in place by tightening said screw, and a laterally extending U-shaped body portion 56, with the free end of the U terminating in a rounded portion 58. Cord 52 normally passes once through the U, and the portion of the cord below the U can be looped over again as at 60 to fasten 90 the parts in place.

100 Because neither plate 44 contains a slot to permit removal of the roller, no accidental vertical displacement of the parts, however violent, can dislodge the roller. With the roller approximately midway between the upper and lower supports, either plate 44 can be rotated about a vertical axis near its rear edge, to move laterally past the end of part 20 or 22, and permit removal of the 105 roller. At the same time, wires 24 can be tensioned by means of adjusting screws 42.

to provide a satisfactorily rigid guide for fittings 16 and 18 without preventing quick removal of the roller as above described.

In the devices of the prior art, rigid rods have been employed in place of wires 24. These rods were much more expensive and also unsatisfactory in service because they were apt to be bent so that the parts could not slide freely, because the fittings slide on them were prone to chatter unless of very elaborate or accurate construction, and because they were conspicuous and unsightly.

In Figs. 4 and 5 I have illustrated an alternative construction of sheet metal, in which shelf 62, corresponding to shelf 34, is bent up at 64 across at 66 and down again at 68 to form a U-shaped housing for a pulley 70 receiving the cord.

Without further elaboration, the foregoing will so fully explain the gist of my invention, that others may, by applying current knowledge, readily adapt the same for use under various conditions of service. It will, for instance, be obvious that a simple change in the positioning of ears 46 to hold plate 44 parallel to the plane of wires 24 instead of perpendicular, as at 46' in Fig. 6, would suffice for positioning the entire structure on supporting surfaces perpendicular to those shown, such as the edge of the window casing close to the window. Many modifications and adaptations may readily be made without eliminating certain features which may properly be said to constitute the essential items of novelty in-

volved, which items are intended to be defined and secured to me by the following claims.

I claim:—

1. In a shade mounting, in combination, 40 fittings for receiving the ends of a shade roller, a plurality of flexible tension wires slidably supporting each fitting, and rigid supports at spaced points for said tension wires, the tension of said wires being such 45 as to permit displacement of said fittings by rotation when positioned intermediate said points, to separate the fittings from the roller.

2. In a shade mounting, in combination, 50 fittings for receiving the ends of a shade roller, a plurality of flexible tension wires slidably supporting each fitting, and rigid supports at spaced points for said tension wires, the tension of said wires being such 55 as to permit displacement of said fittings when positioned intermediate said points, to separate the fittings from the roller.

3. In a shade mounting, in combination, 60 fittings for receiving the ends of a shade roller, flexible tension wire means slidably supporting each fitting, and rigid supports at spaced points on said tension wire means, the tension of said wire means being such 65 as to permit displacement of said fitting when positioned intermediate said points, to separate the fittings from the roller.

In witness whereof, I hereunto subscribe my name this 16th day of November, 1922.

CHAS. H. TILTON.
